(57) **CLAIM**

The ornamental design for a golf tee with ball elevating members and a height adjustment device, as shown and described.

DESCRIPTION

FIG. 1 is a perspective view of a golf tee with ball elevating members and a height adjustment device showing my new design;

FIG. 2 is a front elevational view of the golf tee with ball elevating members and a height adjustment device of FIG. 1, shown partially broken away at the lower end for ease of illustration;

FIG. 3 is a top plan view of the golf tee with ball elevating members and a height adjustment device of FIG. 1;

FIG. 4 is a rear elevational view of the golf tee with ball elevating members and a height adjustment device of FIG. 1;

FIG. 5 is a bottom plan view of the golf tee with ball elevating members and a height adjustment device of FIG. 1;

FIG. 6 is a left side view of the golf tee with ball elevating members and a height adjustment device of FIG. 1, the right side view being a mirror image thereof; and,

FIG. 7 is a perspective view of the golf tee with ball elevating members and a height adjustment device of FIG. 1, shown in use on a golf course.

The matter shown in phantom lines in FIGS. 1, 2, and 7 is for illustrative purposes only and forms no part of the claimed design.
